BUILDING STRUCTURE

Elbert H. Coe, Warners, N. Y.

Application November 15, 1935, Serial No. 49,993

9 Claims. (Cl. 237—53)

This invention relates to certain new and useful improvements in building structure and to the method of forming the same.

It is a well established fact that with the conventionally constructed buildings and heating systems, when the walls of the building are not directly heated, a large percentage of the heat of the human body is lost by radiation during cold weather to the relatively cold building walls with the result that the air in the rooms must be maintained at a relatively high temperature to render said rooms comfortable.

The main object of this invention is to provide a building structure adapted for a residence, store or the like in which the walls are peculiarly adapted for use in connection with heating, ventilating and air conditioning the interior of the building, and which will thereby be maintained in cold weather at a higher degree of temperature than the normal temperature of the human body so that the loss of body temperature through radiation to the walls is substantially eliminated.

Further objects of the invention are to provide a structure of the above mentioned class which is particularly adapted for modern style of architecture, and which is simple, economical and durable in construction.

In carrying out the above mentioned objects, I have provided a building structure composed of concrete and steel wherein the walls and floors are provided with suitable air passages or ducts adapted to be connected with a heater and air conditioning unit. These passages or ducts are so arranged that hot conditioned air leaving the heating unit will be evenly distributed throughout the interior of the floors and walls of the building and conveyed thereby to the interior of the rooms and thence returned to the air conditioning and heating units. This not only provides for very low velocities of air movement but also insures warm walls, floors and ceilings in the winter. Furthermore, the arrangement of the air ducts in the walls and floors of the building are such that in the summer a natural draft may be created therethrough by which cool air will be taken from the basement of the building and circulated through the walls and rooms for cooling and ventilating purposes.

A further object of the invention is to provide dead air spaces in the outside walls of the building for insulating the warm and cold air ducts from each other and from the cold passing inwardly through the outer portion of the walls by conductivity.

A still further object of the invention resides

in providing means whereby the heated air may be circulated through the window structures and thus not only eliminate the cold draft usually present at windows, but also provides for as many windows as may be desired without materially decreasing the total area of the air passages in the walls of the building.

Another object of the invention resides in providing a structure of the above mentioned class wherein the walls may be formed of two different grades or classes of materials cast simultaneously.

Other objects and advantages pertaining to my novel building structure and to the method of forming the same will more fully appear from the following description taken in connection with the accompanying drawings in which:

Figure 1 is a vertical sectional view of a building structure with portions thereof broken away and embodying the various features of this invention.

Figure 2 is a detail horizontal sectional view taken on line 2—2, Figure 1.

Figure 3 is a horizontal cross sectional view through an outer corner of the building taken substantially on line 3—3, Figure 1.

Figure 4 is a detail sectional view taken on line 4—4, Figure 3.

Figure 5 is a side elevation partly broken away of one of the air duct form members and illustrating the same in operative relation with a pair of vertical wall columns.

Figure 6 is a longitudinal sectional view taken on line 6—6, Figure 5, illustrating an intermediate portion of the lower end of the form broken away.

Figures 7 and 8 are horizontal sectional views taken respectively on lines 7—7 and 8—8, Figure 5.

Figure 9 is a detail sectional view taken on line 9—9, Figure 6.

Figure 10 is a detail vertical sectional view illustrating my novel window frame structure and the relation thereof with the air ducts taken substantially in the plane of the line 10—10, Figure 3.

Figure 11 is a side elevation of the furnace indicated in Figure 1 and illustrates the same connected with a suitable air conditioning apparatus.

In Figure 1 of the drawings, I have illustrated a building structure comprising outer side walls 1, inner side walls or partitions 2, floors 3, ceilings 4 and a roof structure 5, all of which are illustrated as being composed of concrete, plaster or the like, which may be reinforced in the usual manner by suitable posts or columns, cross beams, joist and

the like, formed preferably of steel or other suitable material.

In constructing the outer side walls, I preferably use outer and inner side form members 10 and 11 as shown in Figure 3 and a multiplicity of air duct form members 12 as shown in Figure 5. The outer and inner side form members 10 and 11 are each composed of intermediate form sections 13 composed of sheet metal and which are 10 preferably of convenient size for handling. Each section 13 comprises a rectangular base 14 preferably about two feet square although this size may be altered if desired. This base is provided with marginal flanges 15 arranged to extend outwardly from one side of the base portion. The flanges 15 are provided with longitudinally spaced apertures 16 which, when the forms are arranged side by side, are adapted to align with corresponding apertures in the flanges of the adjacent form for the reception of tie bolts 17 which releasably clamp the form sections to each other.

The intermediate wall forms 13 are joined at the corners of the building by outer and inner corner forms 19 and 20 respectively and where 25 necessary, as illustrated in connection with the inner wall in Figure 3, a section as 21 is interposed between the corner sections 19 or 20 and the intermediate wall sections 13 to position these intermediate sections in proper cooperative relation with the opposite wall sections and with the upright columns of the wall. These corner sections 19 and 20 and the sections 21 are each provided with marginal flanges 19', 20' and 21' respectively which correspond in 35 size and arrangement to the marginal flanges 15 of the intermediate sections 13 whereby the sections may be joined to each other by the bolts 17. The corner sections 19 and 20 and the sections 21 are each of substantially the same height 40 as the intermediate sections 13 while the length of these sections is less than that of the intermediate sections.

These upright columns for the outer walls of the building are in two forms; one as 23, is particularly adapted to be used at the corner of the walls, while other columns as 24 are adapted to be used intermediate the corners of the walls and are spaced from the corner columns 23 and from each other a uniform distance depending 50 upon the length of the intermediate wall form sections 13. For instance, if the upright columns are spaced a distance of two feet from each other, the length of the intermediate wall form sections 13 are likewise two feet so that said form sections and columns may be readily mounted in cooperative relation during the forming of the walls in a manner which will hereinafter be more fully explained.

The intermediate columns 24 are, in this instance, formed of two channel members 26 as 60 shown in Figures 2 and 3. These channels are preferably formed from steel plates although structural channels may be used. The channels are mounted back to back in slightly spaced relation. Each of the channel members 26 is provided with a plurality of longitudinally spaced apertures 27 formed in the transverse portion intermediate the longitudinal sides thereof and are spaced apart a distance substantially equal to the 65 height of the intermediate form sections 13. The openings 27 in each channel member are adapted to align with corresponding openings in the other channel member of a respective column and have mounted therein a U-shaped tie clip 28 which, as 70 shown in Figures 3 and 4, extend transversely of

the column members through the openings. The opposed sides of each U-shaped clip 28 are provided with aligned threaded openings. A flanged sleeve member 29 is screw threaded in a respective opening and extends outwardly from the respective side of the tie clip to a position beyond the adjacent side of the channel members 26 with the flange thereof abutting against the adjacent longitudinal sides of the channel members 26 to fixedly secure the clamping sleeves to the columns. These sleeves and clips also function to maintain the column channels in fixed predetermined spaced relation relative to each other.

Each of the sleeves 29 is provided with an internal threaded opening for the reception of a clamping bolt 30 provided for the wall form sections 13, 19, and 21. These clamping bolts 30 are preferably permanently connected with the corresponding side form section and for this purpose, are each provided with a collar 31 fixedly secured thereto in any suitable manner in a slightly spaced relation to the head of the screw. These screws extend through corresponding openings provided in the wall section with the collar 31 positioned against the outer face of the base of the section in retaining clips or straps 32 secured by spot welding or other means to the adjacent portion of the form section. These clamping bolts are preferably mounted in the form section adjacent an end thereof and the outer form sections are preferably secured to the upright columns in reverse order to the inner form sections, as shown in Figure 3, so that the abutting ends of the outer form sections will be arranged in staggered relation relative to the columns to that of the inner form sections to thereby produce a more rigid form structure for receiving the plastic material forming the walls during the pouring thereof.

The corner columns 23 are preferably composed 40 of four upright members, two box shaped members 34 and two channel shaped members 35. The box shaped members are arranged in diagonal relation with the corners of the building while the channel shaped members 35 are positioned intermediate the box shaped members as 45 shown in Figure 3. The outer box shaped member 34 and the adjacent channel shaped members 35 are each provided with longitudinally spaced apertures similar to the aperture 27 in 50 the intermediate channel members 26. These apertures in each channel member are arranged in aligned relation with corresponding apertures in the other channel members for the reception of an L-shaped tie clip 37. These tie clips 37 are 55 each provided with a threaded aperture in the upright leg thereof in which is screw threaded a flanged tie sleeve member 38 constructed similarly to the tie sleeve member 29 associated with the intermediate columns 24 and which, like the sleeves 29, not only maintain the corresponding column members in predetermined cooperative relation with each other, but also receive corresponding clamping bolts 30 therein.

The hereinbefore mentioned conduit form unit 60 65 70 75 80 85 90 95 100 105 110 115 120 125 130 135 140 145 150 155 160 165 170 175 180 185 190 195 200 205 210 215 220 225 230 235 240 245 250 255 260 265 270 275 280 285 290 295 300 305 310 315 320 325 330 335 340 345 350 355 360 365 370 375 380 385 390 395 400 405 410 415 420 425 430 435 440 445 450 455 460 465 470 475 480 485 490 495 500 505 510 515 520 525 530 535 540 545 550 555 560 565 570 575 580 585 590 595 600 605 610 615 620 625 630 635 640 645 650 655 660 665 670 675 680 685 690 695 700 705 710 715 720 725 730 735 740 745 750 755 760 765 770 775 780 785 790 795 800 805 810 815 820 825 830 835 840 845 850 855 860 865 870 875 880 885 890 895 900 905 910 915 920 925 930 935 940 945 950 955 960 965 970

- and 43 are arranged in transverse spaced relation with each other. One of the sets as 42 in this instance, is comprised of three members arranged in parallel spaced relation, while the other set 43 is composed of two members also arranged in parallel spaced relation with each other and which are preferably of less thickness than the block of the other set 42 but of greater width so that the total cross sectional area of 10 the core members of each set are substantially equal to each other. Interposed between the two sets of core members 42 and 43 are a plurality of, in this instance three, vertically disposed core plates 44 arranged in parallel spaced relation with 15 each other substantially midway between the two sets of core blocks 42 and 43, as illustrated in Figure 8. The core plates 44 are of substantially the same width as the core blocks 42 and are secured at their upper ends to the frame 40 in any 20 suitable manner to extend downwardly in alignment with corresponding block members 42.
- At the rear or opposite side of the core blocks 43 are positioned a plurality of, in this instance four, core plates 45 which are secured at their 25 upper ends to the frame 40 and extend downwardly therefrom in longitudinal parallel spaced relation with each other. At the rear or outside of the plates 45 is positioned a core or separating plate 46 also secured at its upper end to the 30 frame 40. The plate 46 as shown in Figure 8, is substantially a U-shaped member in cross section with the longitudinal side portions 46' of the legs thereof extended outwardly from the legs in substantially parallel relation with the transverse 35 portion of the plate and these side portions 46' are arranged one at either side of the set of core blocks 43 in substantially the vertical plane passing through the center of said blocks. The vertical lengths of the plates 44, 45, and 46 are substantially equal to or slightly greater than the 40 height of the wall form sections 13 and slightly less than that of the core blocks 42 and 43. The frame 40 is provided with, in this instance 8, wheels 48 arranged four at either side thereof 45 and which are journaled upon suitable axles 49 secured to the cross pieces 41. The wheels 48 are flanged members and are so arranged that when the frame is mounted in operative relation with the columns 24 or one of the columns 24 and 50 a corner column 23, said wheels will rotatably engage flanges of the column channels as shown in Figure 7 for guiding the frame 40; and, therefore, the core members 42, 43, 44, 45, and 46 during their vertical movement.
- 55 The frame 40 is also provided with means as a cable 50 connected with the upper end thereof to which the cable of a suitable derrick may be attached whereby the frame may be moved vertically relative to the columns to properly position 60 the core members when forming the wall. The axles 49 for the wheels 48 are preferably mounted in elongated horizontally disposed slots 52 provided in the frame 40 as shown in Figure 9, and latch members 53 are pivotally secured to the 65 frame for releasably maintaining the axles in the outer end of the slots in which position of the axles the wheels are maintained in operative engagement with the flanges of the channel members. When it is desired to remove the 70 frame out of engagement with the channel members, this may be readily accomplished without lifting the frame above the upper ends of the channels by swinging the latch members out of holding engagement with the axles 49 after which the axles and wheels may be moved inwardly

relative to the frame to bring the wheels out of holding engagement with the channel members.

In constructing the outer walls of the building the end columns 23 and the intermediate columns 24 are first mounted in any suitable manner 5 upon a foundation wall as 54, Figure 1, with the intermediate columns 24 arranged in equal spaced relation from each other and from the end columns 23, the spacing of these column members being equal to the lengths of the intermediate side wall form sections 13.

A horizontal row of side wall form sections 13, 19, 20, and 21 are then secured to the lower end portions of the columns adjacent the foundation wall 54 by screw threading the screws 30 15 into corresponding sleeves 29 after which the sections may be secured to each other by clamping bolts 17 and the sections brought into proper aligned relation with each other and in suitable spaced relation to the upright columns by the 20 screw threading of the screws 30 into the corresponding sleeves 29 to a greater or less degree. A conduit form unit 12 is then mounted in each space between adjacent column members with the core blocks 42 and 43 resting upon the 25 foundation wall 54 and with the flanged wheels 48 engaging the flanges of adjacent column channels in the manner shown in Figure 7. This connection of the wheels with the columns not only permits ready vertical movement of the 30 frame 40 and core members connected therewith, but also maintains the core members in proper aligned relation with the channel members for forming hot and cold air ducts in the wall and also properly positions the plates 44, 45, and 46 35 for forming corresponding dead air spaces.

When a frame 40 is operatively connected with a pair of column members, the core plate 46 is positioned intermediate the core plates 45 and the outer wall form sections 13 and the longitudinal side portions 46' of these plates are so arranged, that they will extend into the adjacent channel member of the adjacent column and terminate in close proximity to the transverse wall of said channel member so as to form a separating plate between the outer portion of the wall and the inner portion thereof, whereby the outer portion of the wall may be formed of one class of materials such as concrete, while the inner portion of the wall may be formed of a different 40 class or grade of material such as gypsum plaster 45 which may be poured simultaneously with the cement if desired.

After the side forms and core forms have thus been positioned, a course of plastic wall material or materials about the thickness of the height of the outer and inner side forms 13 is first poured and as soon as the wall material such as concrete and plaster has solidified sufficiently, the wall forms and the core frames are moved upwardly and secured in proper relation with the portion of the wall previously poured after which a second course of wall material is poured in the same manner as the first course. After the second course of wall material has sufficiently solidified to maintain its form, the form and core members are again readjusted and a third course of wall material is poured and so on until the side walls are completed.

It will now be observed by referring more particularly to Figures 1 and 3 that each outside wall formed by pouring plastic wall material between the side forms 10 and 11 and around the core blocks and plates of the air duct form members 12 comprises three vertically disposed side 70 75

portions 55, 56 and 57 which are separated by air spaces and connected together by transversely disposed bond portions 58, 59, 58', and 59' formed integral with the side portions. The bond portions 58' and 59' cooperate with the side portions for encasing the columns 24 and the clamping members 28 and 29 associated therewith. The bond portions 58 and 59 are arranged intermediate the bond portions 58' and 59' as shown and 10 cooperate with the latter bond portions and side portions 55, 56, and 57 to form two series of air ducts 60 and 61. The ducts of these series correspond, of course, in cross sectional area to the cross sectional area of the core blocks 43 and 44 15 respectively and as will be understood, extend from within a short distance of the foundation wall 54 upwardly and form an inner and an outer series of air ducts respectively. The inner series of air ducts 61 are connected by respective ports 20 63 with a common manifold 64 which, in turn, is connected by feed pipes 65 with a suitable hot air furnace 66. The manifold 64 may, as indicated in Figure 1, be a horizontally disposed pipe or conduit mounted within the basement of the 25 building to extend along each side wall.

However, it is obvious that these manifolds may be cast integral with the side walls if desired or the air ducts 61 may be connected with each other in any other suitable manner whereby the 30 air heated in the furnace 66 will be evenly distributed to the inner series of air ducts 61 to pass upwardly therethrough.

Likewise, the outer series of air ducts 60 are connected by ports 68 with a suitable manifold 69, 35 common to all of the ducts of the outer series and which, in turn, is connected by return pipes 70 with a suitable air conditioning apparatus 71, which may be associated with the heater 66 or these return pipes may be connected directly with 40 the heater in the usual manner.

It will also be observed by referring to Figure 3 that the outer walls are each provided with three groups of dead air spaces, 72, 73, and 74. The dead air spaces 72 are formed by the plates 44 in the intermediate side portion 56 of the wall. The dead air spaces 73 are formed by the core plates 45 in the outer side portion 55 of the wall in close proximity to the outer series of air ducts 60 and the third group of air spaces 74 50 is produced by the core plate 46 and is arranged intermediate the group of dead air spaces 73 and the outside of the walls.

It will thus be seen that the outer series of air ducts 60 are insulated from the outer surface of the wall by the dead air spaces 73 and 74, while the inner series of air ducts 61 are insulated from the outer series of ducts by the dead air spaces 72 so that the relatively low degree of temperature in the outer series of air ducts will not be 60 carried by conductivity through the intermediate side portion 56 while the high degree of temperature maintained in the inner series of air ducts will be prevented from escaping by conductivity to the outer series of air ducts. It will, therefore, be seen that hot air passing upwardly 65 through the inner series of air ducts 61 will maintain the inner surface of the side walls at a relatively high degree of temperature without excessive loss of heat while relatively cool return air 70 passing downwardly through the outer series of air ducts 60 will be prevented from being excessively chilled due to the insulation afforded by the two outer series of dead air spaces 73 and 74 and whatever cold passing through the outside wall portion 55 by conductivity reaches the outer air 75

ducts 60 will be carried downwardly by the return current of air to the heater 66 where the air is warmed before passing upwardly through the warm air ducts 61.

It will be readily understood that during the construction of the outer walls, the inner walls or partitions 2, floors 3, and ceilings 4 may also be formed. The inner walls or partitions 2 like the outer walls, are preferably provided with two series of air ducts 76 and 77 which may be formed 10 simultaneously with the construction of the walls by use of two sets of core blocks as 42 mounted upon a suitable carriage or frame as 40. It will thus be seen that the inner walls or partitions like the outer walls, comprise 3 vertical side portions, an intermediate portion 56' and two side portions 57'. These air conduits 76 and 77 are preferably of substantially the same size and formation and are maintained in communication with the inner series of air ducts 61 provided in the outside walls by means of suitable passages or conduits 78 formed intermediate the floors 3 and ceilings 4 in any well known manner which it is believed to be unnecessary to further describe in this application. 20

The vertical hot air ducts 61, 76, and 77 are provided with ports or restricted passages 80 formed in the side portions 57' of the inner walls 2 and the side portion 57 of the outer walls 1 adjacent the ceiling of the rooms defined by these walls by suitable core members 82, Figure 3, inserted into suitable apertures provided in the inner form sections 11. Likewise, the outer series of air ducts 60 formed in the outer walls are maintained in communication with the rooms of the building near the lower portion thereof by means of restricted air ports or passages 81 formed in the intermediate and inner side portions 56 and 57 and the bond portions 59 by core members 83. 30

It will now be readily understood that hot air passing from the furnace 66 into the manifold 64 will pass from said manifold upwardly through the inner or hot air ducts 61 in the outer walls 1 and will also pass through the air ducts 78 45 provided intermediate the floors 3 and ceilings 4 and thence upwardly through the air ducts 76 and 77 provided in the inner walls and through ports 80 into the upper portions of the rooms defined by said walls adjacent the ceiling. This 50 warm air then circulates downwardly through the rooms and as it becomes cooled, it will pass outwardly through the ports 81 into the outer series of air ducts 60 and thence back to the furnace 66. The air passing from the inner or hot 55 air ducts 61 into the conduits 78 provided in the upper floor of the building may pass outwardly through suitable apertures provided in the floor into the interior of the attic and thence out through ports 81 into the outer series of air ducts 60. 60

Furthermore, if desired, the roof of the building may be provided with a series of air ducts 83 in communication with corresponding air ducts 60. Ports or restricted passages 84 are 65 shown for maintaining the ducts 83 in communication with the attic.

The roof is also provided with one or more ventilators 85, in communication with the roof ducts 83 so that when the outer walls of the 70 building are subjected to a relatively high degree of temperature as that produced during the summer season, the heat passing by conductivity through the outer portions of the side walls into the outer series of ducts 60 will heat the air 75

contained in said ducts and cause the same to rise and pass off through the ventilator thereby creating an up-draft which, when the dampers as 81 provided in the return pipes 70 are closed, 5 will draw air from the lower portions of the rooms through the ports 81 and carry the same upwardly out through the ventilator while cool air from the basement will be drawn upwardly through the heater 66 and pipe 65 to the inner 10 series of air ducts 61 and thence through the ports 80 into the upper portion of the rooms and thereby maintain the interior of the building at a relatively cool degree of temperature by natural ventilation. It is to be understood that 15 when the system is functioning as above indicated, an opening is provided in the wall of the basement as by opening a window while a damper as 71' provided in the air conditioning apparatus 71 is opened to provide a complete circulation 20 passage which is formed by the air conditioning apparatus 71, heater 66, conduit 65, ports 63, air ducts 61, 78, 76, and 77 and ports 80 through which the cool air in the basement may readily pass to the interior of the rooms.

25 I have provided a novel form of window structure which comprises in providing a rectangular frame as 88 for each window composed preferably of sheet metal having the upper and lower sides thereof provided with apertures 89 and 90 corresponding in cross sectional area to the ducts 60 and 61 respectively and which are adapted to align with said ducts when the frame is mounted in the outer side walls. These frames are each provided with three panes of glass as indicated 35 by broken lines at 91, 92, and 93, Figure 3, arranged one at either side of the openings 89 and 90 and one intermediate said openings to form separate passages aligned with respective air ducts intercepted by the window frame. These 40 passages through each window provide means whereby air will circulate through the ducts intercepted by the windows in the normal manner; that is, hot air passing upwardly through the inner air ducts 61 will pass outwardly through 45 the corresponding window passage between the panes of glass 92 and 93 and then through openings 80 into the interior of the room, while the return air passing downwardly through the outer series of ducts 60 will pass through the passage 50 formed by the panes of glass 91 and 92, and thence in the conventional manner to manifold 69 and furnace 66.

While I have shown the core blocks 42 and 43 as each being solid unitary members, I do not 55 wish to be limited to such construction, as core blocks of various other forms and constructions may readily be used in lieu of those shown. This is particularly true where it is desired to maintain the opposite sides of the air ducts 60 and 61 formed thereby straight and parallel instead of in non-parallel relation as may be the case where the core blocks are given sufficient draft to enable them to be easily withdrawn from the wall material. For example, the core blocks may 65 be provided with a suitable coating of rubber, or they may be of a collapsible nature whereby the cross sectional area of the blocks may be reduced before withdrawing the blocks from the casting position.

70 Furthermore, in place of the dead air spaces 72, 73, and 74, I may utilize standard insulating material provided in sheet form, or I may use such insulating material in conjunction with 75 these air spaces, in which case, the air spaces

would be of such form and size as to readily cooperate with the insulating material.

It will thus be readily understood that although I have shown and particularly described the preferred embodiment of my invention, I do not 5 wish to be limited to the exact construction shown or to the method of construction disclosed herein as various changes therein may be made without departing from the spirit of the invention as set forth in the appended claims.

16 I claim:

1. A hollow wall construction for a building comprising three vertical side portions separated by air spaces and connected at spaced intervals by vertically disposed bond portions which divide the 15 air spaces into two series of vertically extending air ducts, said wall being provided with two series of horizontally disposed restricted air passages, one series of air passages for each series of air ducts whereby one series of air passages connect the interior of the building with one of the 20 series of vertically extending air ducts and the other series of air passages connect the interior of the building with the other series of vertically extending air ducts.

2. A structure as in claim 1 having air conveying means for operatively connecting each series of air ducts with a hot air furnace.

3. A device as in claim 1 having air conveying means for operatively connecting one of said series of air ducts with the air intake of a hot air furnace and separate air conveying means for operatively connecting the other series of air ducts with the air exhaust of said hot air furnace.

4. A device as in claim 1 wherein one of the 35 vertical side portions is provided with a series of vertically extending dead air passages.

5. A device as in claim 1 wherein the wall is provided with two series of dead air spaces arranged 40 one at either side of one of the series of air ducts.

6. A hollow wall construction for a building comprising three vertical side portions separated by air spaces and connected at spaced intervals by vertically disposed bond portions which divide the air spaces into two series of vertically extending 45 air ducts, bond portions associated with one series of air ducts being arranged in staggered relation with bond portions associated with the other series of air ducts, said wall being provided with a series of horizontally disposed restricted air passages extending through one of the side portions thereof for connecting the adjacent series of air ducts with the interior of the building, and a second series of horizontally disposed restricted air 50 passages extending through two adjacent side 55 portions and the bond portions interposed therebetween for connecting the other series of air ducts with the interior of the building.

7. A device as in claim 6 having separate air conveying means for connecting one of the series 60 of air ducts with the air intake of a hot air furnace and the other series of said air ducts with the air exhaust of said hot air furnace.

8. A building structure having a side wall there-of defining upper and lower rooms and provided 65 with two series of air ducts in communication respectively with the upper and lower portions of said rooms, a window frame mounted in said wall and intercepting certain of the ducts of both series, said frame being provided with means including three window panes arranged in parallel spaced relation with each other for providing a pair of air passages therethrough for maintaining the corresponding ducts of said series in communication with each other, and air conveying 70 75

means for connecting one of said series of air ducts with the feed passage of a heating unit and the other series of ducts with the return passage of said heating unit.

- 5 9. A building structure having outer and inner side walls and floor and ceiling structures defining a plurality of rooms, each of said side walls being provided with two series of air ducts arranged in transverse spaced relation with each other, air ducts in the floor and ceiling structures maintaining each series of air ducts in the inner side wall in communication with the inner adja-

cent series of air ducts in the outer side wall, air passages connecting the series of air ducts in the inner side wall with the room adjacent thereto, separate air passages connecting the outer series of air ducts in the outer wall with the room adjacent thereto, and air conveying means for connecting one of said series of air ducts in the outer wall with the feed passage of a heating unit and the other series of air ducts in the outer wall with the return passage of said heating unit.
